UNITED STATES PATENT OFFICE.

BENJAMIN F. GILBERT, OF PHILADELPHIA, PENNSYLVANIA.

RAIL JOINT AND FASTENER.

1,081,823.

Specification of Letters Patent.

Patented Dec. 16, 1913.

Application filed August 18, 1913. Serial No. 785,414.

To all whom it may concern:

Be it known that I, BENJAMIN F. GILBERT, a citizen of the United States, residing at Philadelphia, in the county of Philadelphia and State of Pennsylvania, have invented a new and useful Rail Joint and Fastener, of which the following is a specification.

The present invention relates to improvements in rail joints and fasteners, one object of the invention being the provision of a two membered device adapted to fit upon opposite sides of the web and base of a rail, either at the joints thereof or at intermediate portions, and also to carry means for engaging two ties, the two members being bolted to and through the web of the rail so as to brace the rail against lateral movement and to hold the ties relatively to the rail.

A further object of the invention is the provision of a tie and rail fastener, which will prevent the rails from being turned due to the thrust thrown thereupon by trains, and which will also permit the necessary longitudinal expansion and contraction in the rails.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a top plan view of the complete device when in use. Fig. 2 is a side elevation thereof. Fig. 3 is an end elevation looking in the direction of the arrow in Fig. 1.

Referring to the drawings, the numerals 1 and 2 designate two ties, and 3 and 4 the two rails which are joined and properly connected by means of the tie and fastening members 5 and 6. Each of these two members is provided with means for properly seating upon the two ties 1 and 2, such means, as clearly shown, constituting the two flanges 7 and 7', 8 and 8' of the member 5, and flanges 7^a—7^b and 8^a—8^b of the member 6.

As clearly shown in Fig. 3, these flanges extend a sufficient distance upon the ties to prevent any lateral movement of the parts

relatively to the tie, and form a relatively large receptacle for the ties. A recess 10 is provided in the flanges 7^a and 8^a for the reception of the tongue 11 carried by the respective flanges of the member 5. Thus in order to separate the members 5 and 6 they are moved so as to disengage the tongue 11 from its respective recess 10. The spike apertures 12—12' are provided in the respective flanges at the ends of the members 5 and 6, so that spikes may be driven thereto and into the tie. Thus the members are locked after being properly positioned relatively to the rail and provide a fastening 65 and chair or rail brace for the rail upon the base and web. The member 5 is also provided with the recessed portions 13 directly below the rail base of the supporting portion for the reception of the tongues or projections 14 of the member 6, the respective tongues 14 being so disposed as to extend below the base of the rail and constitute a rail base engaging portion that projects to 70 interlock with the rail base receiving portion of the member 5.

A rail brace 15 is carried by the member 5, while the co-operating rail brace 15' is carried by the member 6, the same being constructed, as clearly shown in Fig. 3, to engage the web of the rail and the under side 85 of the head or tread thereof. By this means, both rails as illustrated in Figs. 1 and 2 are braced for the full distance between the two ties 1 and 2 and from points at the outer 90 faces thereof.

The two shouldered portions 16—16' are carried by the member 5 at both ends thereof, and provide the channel or recess 17, which is provided with the spike receiving opening 18, said opening being disposed about a portion of the base of the rail so that a spike driven therethrough and into the tie will have its head engage the portion of the rail base observable through the slot 100 17 and thus hold the rail seated upon the member 5. A similar structure is provided at the end of the member 6, there being provided recessed portions 19—19' for the reception of the heads of the locking bolts 20, 105 said bolts being extended through the rail bracing portions 15 and 15' to lock the members 5 and 6 relatively to the rail. These bolts are extended through apertures (not shown) in the web of the rail and these apertures are of such a size as to permit of the necessary longitudinal movement of the 110

2
rail due to expansion and contraction. The intermediate bolts 21 are also connected through the members 5 and 6 and also the adjacent portion of the web of the rails 3 5 and 4.

From the foregoing description, it will be seen that the members 5 and 6 are provided with means for engaging the ties and thus for holding the ties relatively together, and 10 at the same time engage the rail, or both rails at a joint, upon opposite sides to be clamped thereto in such relation as to hold the rail against tilting, the spikes driven in the apertures 12 assisting in preventing any 15 tearing of the members 5 and 6 from the tie.

What is claimed is:

1. A rail joint and fastener, including two members, two tie receiving flanges carried by each member, a rail brace carried by each 20 member, coöperable means carried by both members to hold the members against independent longitudinal movement, and coöperable means carried by the flanges of both members to hold the members against independent vertical movement.

2. The combination with two abutting rails and two ties, of a rail joint and fastener, including two members, each member being provided with two depending parallel 30 flanges adjacent the ends thereof to receive the respective ties, fastening devices pierc-

ing the outer flanges of both members and the tie to hold the members against separation, a rail brace carried by each member the full length thereof and shaped to receive a portion of the base and web of the rail, and coöperating means carried by the members for locking the members against independent longitudinal movement.

3. The combination with two abutting 40 rails and two ties, of a rail joint and fastener, including two members, each member being provided with two depending parallel flanges adjacent the ends thereof to receive the respective ties, fastening devices piercing the outer flanges of both members and the tie to hold the members against separation, a rail brace carried by each member the full length thereof and shaped to receive a portion of the base and web of the rail, coöperating means carried by the members for locking the members against independent longitudinal movement, and fastening devices piercing the rail braces and the adjacent portion of the web of the rails.

In testimony that I claim the foregoing as my own, I have hereto affixed my signature in the presence of two witnesses.

BENJAMIN F. GILBERT.
